UNITED STATES PATENT OFFICE

JOSEPH E. BERGER, OF BLOOMFIELD, NEW JERSEY, ASSIGNOR TO SCOVILL MANUFACTURING COMPANY, OF WATERBURY, CONNECTICUT, A CORPORATION OF CONNECTICUT

DESIGN FOR A BOX OR SIMILAR ARTICLE

Application filed December 1, 1928. Serial No. 29,078. Term of patent 7 years.

To all whom it may concern:

Be it known, that I, JOSEPH E. BERGER, a citizen of the United States, residing at Bloomfield, in the county of Essex, State of New Jersey, have invented a new, original, and ornamental Design for a Box or Similar Article, of which the following is a specification.

This invention relates to a new, original and ornamental design for a box or similar article, substantially as shown in the accompanying drawing forming a part of this specification, in which—

Figures 1, 2 and 3 are top, side, and end views respectively of the box showing the new design.

I claim:

The ornamental design for a box or similar article as shown.

JOSEPH E. BERGER.
